UNITED STATES PATENT OFFICE.

CHARLES WHITE, JR., AND JAMES ANDERSON, OF VERSAILLES, INDIANA.

CONDITION-POWDER.

SPECIFICATION forming part of Letters Patent No. 298,433, dated May 13, 1884.

Application filed January 25, 1884. (No specimens.)

To all whom it may concern:

Be it known that we, CHARLES WHITE, Jr., and JAMES ANDERSON, citizens of the United States, residing at Versailles, in the county of Ripley and State of Indiana, have invented a new and useful Condition-Powder, of which the following is a specification.

Our invention relates to a compound or powder for the treatment of contagious diseases in cattle, arising from fever and terminating in inflammation of the lungs, the object being to provide a valuable compound for safe and effectual treatment for the diseases named.

The invention consists in the following ingredients combined in about the proportions specified: pulverized fenugreek, two ounces; pulverized nitrate of potassium, two ounces; pulverized elecampane, two ounces; pulverized sulphate of iron, two ounces; pulverized gentian, two ounces; pulverized gum-acacia, one ounce. The above ingredients are thoroughly mixed and given in the form of a powder, a table-spoonful of which constitutes a dose.

Before giving the above-described powder, eighty drops of tincture of aconite are given, thirty drops each hour. A dose of the powder is then given, and the aconite continued for two more hours, or two doses of thirty

drops each. The powder is then given, a table-spoonful every four hours, until cured, the aconite being discontinued after four doses of thirty drops each have been given.

By the use of the above-described powder a ready and effective remedy is found for fever or inflammation of the lungs.

We are aware that condition-powders containing fenugreek, niter, and gentian, and also others containing fenugreek, gentian, and elecampane, with other ingredients, are not new; but,

Having fully described our invention, what we claim, and desire to secure by Letters Patent, is—

The herein-described compound, consisting of pulverized fenugreek, pulverized nitrate of potassium, pulverized elecampane, pulverized sulphate of iron, pulverized gentian, and pulverized gum-acacia, in about the proportions specified.

In testimony that we claim the foregoing as our own we have hereto affixed our signatures in presence of two witnesses.

CHARLES WHITE, JR.
JAMES ANDERSON.

Witnesses:

NICHOLAS CORNET,
FRANK M. BEDUNNAH.
